UNITED STATES PATENT OFFICE.

ISIDOR KITSEE, OF PHILADELPHIA, PENNSYLVANIA, ASSIGNOR TO CHARLES E. WILSON, OF SAME PLACE.

ELECTRIC TELEGRAPHY.

SPECIFICATION forming part of Letters Patent No. 651,013, dated June 5, 1900.

Application filed May 20, 1898. Serial No. 592,338. (No model.)

To all whom it may concern:

Be it known that I, ISIDOR KITSEE, of the city and county of Philadelphia, State of Pennsylvania, have invented certain new and useful Improvements in Electric Telegraphy, of which the following is a specification.

My invention relates to electric telegraphy. Its object is to convert the rays of a receiver consisting of a vacuum-tube into sound or to record.

Broadly speaking, my invention consists in the conversion of the glow-rays of the vacuum-tube, generated therein with the aid of an interrupted or alternating current, into sound or record.

Referring to the drawings, Figures 1 and 2 are diagrammatic views embodying my invention, and Fig. 3 is a sectional view of a globe of a modified form.

In Fig. 1, A is a vacuum-globe or similar device provided, as is usually the case, with the two terminals of a circuit connected to a source of current. In proximity to the globe A is the selenium stick or cell B, connected with one of its terminals to the positive pole of the battery C. The other terminal of the selenium-cell B connects with one end of the coil of the electromagnet D. Globe A and selenium-cell B are inclosed in the dark chamber A'. In the circuit with the cell B is the battery C and electromagnet D. Connected to the same battery is the second selenium-cell B'. Inclosed in the dark chamber A² and in series with said cell is the electromagnet D'. To persons versed in the art it will be at once apparent that if resistance of B and D plus their circuit is alike to the resistance of B' and D' plus their circuit the flow of the current in both circuits will be equal and the electromagnets D and D' will exert, if oppositely wound, an equally-opposing force on an armature placed at equal distance between them, and such armature will therefore be at rest; but should, through any cause whatso-

ever, the resistance of one of the two circuits be lowered the flow of the current through both circuits will be an unequal one and an armature placed between both electromagnets will be attracted through the greater force of one or the other. Now it is well known that selenium in its crystalline state is very sen-

sitive to the action of light and, as was proven by experiments, the rays of the vacuum-globe lower the resistance of such selenium even more than would be the case under ordinary illumination of same strength. As long, therefore, as the globe A is not traversed by the electrical current the conditions of both the dark chambers A' and A² are equal; but as soon as the terminals of the globe A are connected to the source of current the inner space of said globe becomes illuminous, thereby lowering the resistance of the selenium-cell B and as a result destroying the equilibrium between the two circuits. Between the two electromagnets D and D' is placed the armature R, connected to the springs d¹ d². This armature is provided with a contact-point d, in proximity to which is placed the adjustable contact-point d'. The lower part of the movable armature is connected to one pole of the battery G, the other pole of which connects to one terminal of the electromagnet of the sounder F, the other terminal of said electromagnet being connected to the adjustable contact-point d'. If telegraphing or signaling is done according to the Morse or alphabetical code, a shorter glow-time representing a dot and longer glow-time representing a dash, it is obvious that the armature R will, if the adjustments are properly made, close the circuit containing the local sounder F in correspondence with the glow of the globe A. We therefore have, as far as the receiving operator is concerned, the usual sound-receiver. It is also self-evident that instead of or in conjunction with the sounder F any well-known recording instrument may be placed in the circuit.

In Fig. 2 I have placed the sounder F in direct circuit with the selenium-cell B, so as to illustrate the probability of translating the light-signals into sound-signals without the addition of the relay, as illustrated in Fig. 1.

In Fig. 3 the selenium-cell B is placed in the inner space of the globe A. In all cases, but more so in the last instance—that is, when the selenium is placed in the inner space of the globe—its resistance is greatly lessened, even if the light-rays of the vacuum-globe are not perceptible to the naked eye.

Having now described my invention, what

I claim as new, and desire to secure by Letters Patent, is—

1. In electricity, a device for transforming the luminosity of a vacuum-globe into sound or record, consisting of a vacuum-globe connected to a source of rapidly recurring or alternating impulses of electricity, a second circuit containing a generator of electricity, a translating device and selenium, said selenium being placed in suitable relation to the action of said vacuum-globe.
2. In electricity, a translating device consisting of a vacuum globe or device similar in its action containing selenium, the vacuum-globe and the selenium being adapted each to be connected to a separate circuit containing generators of electricity and translating devices.
3. In electricity a device for changing or

altering the flow of a current in a local circuit, which consists of a vacuum-globe connected to a source of rapidly recurring or alternating impulses, a local circuit containing a translating device, generators of electricity and selenium, said selenium being placed in juxtaposition to said vacuum-globe.

4. In a system of telegraphy, a receiver consisting of a vacuum-globe, a local circuit containing a translating device and battery, and a selenium-cell, substantially as and for the purpose specified.

In testimony whereof I sign my name this 19th day of May, 1896, in the presence of two subscribing witnesses.

ISIDOR KITSEE.
